Jun. 12, 2018 (KR) 30-2018-0027052

The ornamental design for a container for fruit or vegetable wash, as shown and described.

(51) **LOC (11) Cl.** **07-07**

DESCRIPTION

(52) **U.S. Cl.** **D7/602**

FIG. 1 is a perspective view of my new design;
FIG. 2 is a front elevational view thereof, the opposite side
being a mirror image;

(58) **Field of Classification Search**

FIG. 3 is a side elevational view thereof, the opposite side
being a mirror image;

USPC D7/602, 629, 630, 538-549, 667;
D9/424, 425, 430-432
CPC A47J 36/24; A47J 36/26; A47J 36/2405;
A47J 36/12; A47J 36/00; A47J 39/00;
A47J 39/02

FIG. 4 is a top plan view thereof;
FIG. 5 is a bottom plan view thereof;

See application file for complete search history.

FIG. 6 is a cross-sectional view taken along line VI-VI in
FIG. 4; and,
FIG. 7 is a cross-sectional view taken along line VII-VII in
FIG. 4.
